Primary Examiner — Catherine Tuttle(74) *Attorney, Agent, or Firm* — Sterne, Kessler, Goldstein & Fox P.L.C.**(57) CLAIM**

The ornamental design for a bottle pump, as shown and described.

DESCRIPTION

FIG. 1 is a front perspective view of a bottle pump showing my new design;

FIG. 2 is a side view thereof, the opposite side view being a mirror image thereof;

FIG. 3 is a rear view thereof;

FIG. 4 is a front view thereof;

FIG. 5 is a top view thereof; and,

FIG. 6 is a profile view taken along line 6-6 in FIG. 5. The broken lines in the Figures are included for the purpose of illustrating associated environmental structure which forms no part of the claimed design.
